US00D553563S

(12) **United States Design Patent** (10) **Patent No.:** **US D553,563 S**
Pizzi (45) **Date of Patent:** **** Oct. 23, 2007**

(54) **ELECTRIC BICYCLE BATTERY PACK**

(75) Inventor: **Larry Pizzi**, Santa Monica, CA (US)

(73) Assignee: **Currie Technologies, Inc.**, Chatsworth, CA (US)

(**) Term: **14 Years**

(21) Appl. No.: **29/270,395**

(22) Filed: **Dec. 20, 2006**

(51) **LOC (8) Cl.** **13-02**

(52) **U.S. Cl.** **D13/103; D13/106**

(58) **Field of Classification Search** D13/102-106, D13/110, 118-119, 184; 429/96-100, 163, 429/176

See application file for complete search history.

(57) **CLAIM**

The ornamental design for electric bicycle battery pack, as shown and described.

DESCRIPTION

FIG. 1 is a perspective view of the electric bicycle battery pack

FIG. 2 is a left side elevational view of the electric bicycle battery pack

FIG. 3 is a front elevational view of the electric bicycle battery pack

FIG. 4 is a right side elevational view of the electric bicycle battery pack

FIG. 5 is a rear elevational view of the electric bicycle battery pack

FIG. 6 is a top plan view of the electric bicycle battery pack; and,

FIG. 7 is a top plan view of the electric bicycle battery pack.

1 Claim, 6 Drawing Sheets

FIG. 1

FIG. 2

FIG. 3

FIG. 4

FIG. 5

FIG. 6

FIG. 7
